CLAIM

The ornamental design for a gemstone, as shown and
described.

DESCRIPTION

FIG. 1 is a top plan view of a gemstone according to this
invention;

FIG. 2 is a side elevational view, the opposite side view
being a mirror image; and,

FIG. 3 is a bottom plan view.

Since the invention is for a round gemstone, the front and
rear views would be the same as the side elevational views,
so that no views are provided.
